Inventor
S. S. Connor:

UNITED STATES PATENT OFFICE.

SYDNEY S. CONNOR, OF AMITE CITY, LOUISIANA.

HAND-GRENADE.

SPECIFICATION forming part of Letters Patent No. 760,614, dated May 24, 1904.

Application filed August 10, 1903. Serial No. 168,947. (No model.)

To all whom it may concern:

Be it known that I, SYDNEY S. CONNOR, a citizen of the United States, residing at Amite City, in the parish of Tangipahoa and State 5 of Louisiana, have invented certain new and useful Improvements in Hand-Grenades; and I do hereby declare the following to be a full, clear, and exact description of the invention, such as will enable others skilled in the art to 10 to which it appertains to make and use the same.

My invention relates to new and useful improvements in hand-grenades or devices for throwing on fires to extinguish the flames.

One object of my invention is to provide an 15 improved device of this character which will be very efficient in use and at the same time be simple and of comparatively inexpensive construction.

A further object is to provide means for 20 readily and thoroughly mixing the contained chemicals just before using the device.

With these and other objects in view the invention consists of certain novel features of construction, combination, and arrangement 25 of parts, as will be more fully described, and particularly pointed out in the appended claims.

In the accompanying drawings, Figure 1 is a side elevation of my improved hand-grenade. 30 Fig. 2 is a vertical sectional view through the same. Fig. 3 is a horizontal sectional view taken on the line 3 3 of Fig. 2.

In the embodiment of my invention as illustrated in the drawings, the numeral 1 denotes 35 a receptacle or container, which may be of any desired size, shape, and material, but which is preferably a frangible glass bottle of rectangular form, as shown. The interior of said bottle is formed with two or more non- 40 communicating compartments adapted to contain chemicals which when mixed and thrown upon a fire will produce a flame-extinguishing gas. As illustrated in the drawings, two of said compartments are provided, the lower 45 one, 3, being separated from the upper one, 4, by a frangible partition 5. The lower compartment 3 is adapted to be filled with a chemical solution, preferably sulfuric acid, by pouring the same down a small vertical filling-tube 50 6, formed within the compartment 4 and hav-

ing its upper end opening at the top of the bottle. A cork, plug, or other closure 7 is inserted in said tube to close and seal the compartment 3. The compartment 4 is adapted to contain a chemical solution, preferably bicarbonate of ammonium, which is poured into the same through an opening 8 in the top of the bottle. Said opening is closed by a cork, plug, or other closure 9, in which a sliding striker or hammer 10 is mounted. Said 55 striker comprises a head 11 and a stem or handle 12, which slides through an opening in said cork or stopper 9 and which is provided at its upper or outer end with a cross-pin or stop 13, which limits the downward or inward 60 movement of the striker. The head 11 of the striker is disposed within the compartment 4, being inserted through the opening 8, and is adapted to rest upon the top of the partition 5 when the device is not being used. 70

In using the device the bottle 1 is grasped and the outer end of the stem 12 of the striker is given a light tap or blow to force the same inwardly, so that its head 11 will break the partition 5. The bottle is then inverted and 75 shaken to cause the heavier acid to drop and become thoroughly commingled with the other, and, if desired, the stem or handle of the plunger may be reciprocated to cause its head 11 to agitate the mixture. The bottle is then 80 thrown with sufficient force to break at the base of the fire, and the gas generated from the chemical will quickly extinguish the flames, as is well known. The bottles are adapted to be supported in frames or baskets upon the 85 walls of the rooms of a building, so as to be easily accessible in case of fire.

It will be seen that by holding the chemicals separate until ready to be used and then thoroughly mixing and agitating them just 90 prior to their being sprinkled upon the fire will render the device extremely effective and produce a result that cannot be obtained when the chemicals are not thoroughly commingled before the bottle is broken. 95

From the foregoing description, taken in connection with the accompanying drawings, the construction and operation of the invention will be readily understood without requiring a more extended explanation. 100

Various changes in the form, proportion, and the minor details of construction may be resorted to without departing from the principle or sacrificing any of the advantages of this invention.

Having thus fully described my invention, what I claim, and desire to secure by Letters Patent, is—

1. A hand-grenade, comprising a frangible container, having upper and lower compartments formed by a horizontal frangible partition and adapted to contain fire-extinguishing chemicals, and a striker within said container adapted to be supported by the partition and to be raised and forced downward to break said partition to open communication between said compartments.
2. A hand-grenade comprising a frangible container having compartments separated by a frangible partition and adapted to contain fire-extinguishing fluids, a filling-tube for one of said compartments, a filling-opening in the other compartment, a closure for said opening, a sliding striker mounted to reciprocate

in said closure and adapted to break said partition, substantially as described.

3. A hand-grenade, comprising a vertical frangible container having a horizontal transverse frangible partition forming upper and lower compartments, an inlet in the top of the upper compartment for filling said compartment, an inlet for the lower compartment extending downward between the upper compartment and the outer wall of the container, to fill the lower compartment, closures for said compartments, and a striker extending through the top of the upper compartment and into said compartment and adapted to rest upon said partition and to be employed to break the same to open communication between said compartments.

In testimony whereof I have hereunto set my hand in presence of two subscribing witnesses.

SYDNEY S. CONNOR.
